CHARLES VALLONE, OF BUFFALO, NEW YORK, ASSIGNOR TO BARCALO MANUFACTURING COMPANY, OF BUFFALO, NEW YORK

TOOL HOLDER OR TOOL SET

Application filed March 27, 1931. Serial No. 525,673.

This invention relates to improvements in tool holders or tool sets such as open end wrench sets comprising a group of wrenches of graduated sizes, each having a shank or handle provided with end enlargements or jaws, and a holder or binder by which the wrenches of the set are bound or held together in an orderly arrangement adapting the set to be handled or treated as a unit, but nevertheless so as to permit the ready removal and replacement of any desired wrench or wrenches of the set.

One object of the invention is to provide a practical and desirable holder of improved, but simple and inexpensive, construction which is adapted to bind or hold a set of wrenches, or the like, in a prescribed arrangement and to be opened to permit the ready insertion and removal of the wrenches single or collectively. Other objects of the invention are to provide a holder of this sort which is composed entirely of wire and comprises a body portion in which the tools are placed, and a movable retainer or member which is adapted to be releasably secured in position to retain the tools in place in the body and to be opened to release the tools; which comprises a body and a hinged retaining member, each formed of a single piece of wire bent into the required shape, releasable securing means for the retaining member formed by integral, interengaging portions of the body and retaining member; and which is of improved construction and has the advantages hereinafter described and set forth in the claims:

In the accompanying drawing:

Fig. 1 is a side elevation of an open end wrench set including a holder embodying my invention.

Fig. 2 is a perspective view of the holder alone.

Fig. 3 is a transverse section of the wrench set on line 3—3, Fig. 1, showing the retaining member in closed or retaining position.

Fig. 4 is a similar view showing the retaining member opened.

Fig. 5 is a sectional plan view of the wrench set on line 5—5, Fig. 1.

Fig. 6 is a perspective view showing a modified form of the holder.

The holder comprises a body member 10 and a movable retaining member 11, which are hinged or pivotally connected to each other, and each of which is formed by a single wire, rod or strip bent to the form illustrated in the drawing.

In the construction shown in Figs. 1 to 5 the body member comprises oppositely inclined legs or end bars 12 connected at one side of the holder by a longitudinal side bar 13. Similarly, the retaining member comprises legs or end bars 15 which, in the closed position of this member, are opposite to and incline correspondingly with the end bars 12 of the body, and are connected at their ends which are nearer together by a longitudinal side bar 16 at the same side of the holder as the bar 13. At the opposite side of the holder the end bars 15 and 12 are hinged or pivotally connected to each other, preferably by end cross bars 14, which extend transversely from the lower or more widely spread ends of the end bars 12 of the body and are formed with eyes 17 passing through or interengaging with eyes 18 formed on the ends of the bars 15. The retaining member is thus adapted to swing toward and from the body member and it is releasably retained in closed position, or in position to retain the wrenches in the holder by the engagement of parts at the free ends of the body and retaining members.

Preferably, the side bars 13 and 16 of the body and retaining member are oppositely offset transversely from the inclined end bars 12 and 15 to which they are joined and the offset portions joining one of the side bars 13 or 16 to its end bars, are formed with bends or corrugations 19 adapted to pass over and spring or snap into holding engagement with the side bar of the other member of the holder. For instance, as shown, the bends 19 are formed in the offset or cross portions connecting the side bar 16 to the end bars 15 of the retaining member. The free ends of the body and retaining member are thus releasably held in engagement by the inherent elasticity of the two parts of

the device. The side bars 13 and 16 are also preferably provided between their ends with bends or humps 20 which serve as finger pieces or holds for the fingers in opening 5 the holder.

The wrenches 21, which are of graduated sizes, are placed side by side or flat-wise parallel with each other in the body of the holder as shown in Figs. 1, 3 and 4 with the inclined legs or end bars 12 and 15 of the body and retaining member crossing and engaging the opposite edges of the shanks of the wrenches at or adjacent to the inner ends of the end enlargements or jaws 22 of the wrenches. That is, when the retaining member is in closed position, the holder extends about and binds the wrenches together with the inclined legs or end bars 12 and 15 engaging the opposite edges of the wrench shanks so as to hold the wrenches from separation and displacement transversely, and in addition, the inclination of the end bars 12 and 15 is such that they are also adapted to engage the shoulders or inner ends of the jaws of the wrenches and thereby substantially prevent the wrenches from shifting lengthwise or longitudinally in either direction in the holder. The wrenches are thus retained in the intended stepped order in the holder, but any one or more of the wrenches can be readily removed from the holder by disengaging the free end of the retaining member from the body of the holder and swinging it outwardly to open position. It will be noted that the legs and bars 12 and 15 of the holder extend crosswise of the narrow edges of the wrench shanks or, that is, transversely of the parallel planes in which the wrenches are disposed so that, when the holder is opened any one or more of the wrenches may be removed from the holder through the open side thereof without removing or disturbing the remaining wrenches.

25 The modified construction shown in Fig. 6 is similar to that described, but, in addition, the inclined legs or end bars 12a of the body are bent or corrugated to form transversely extending separators 23 which form individual seats or pockets 24 to receive and hold the shanks of the wrenches. The shank of each wrench is adapted to seat or rest in a pair of the seats 24 thus formed in the two legs or end bars 12a. With the wrenches thus separately retained in place, each in its own seat, in the holder, if one or more of the wrenches is, or are, removed from the holder, the remaining wrenches will, nevertheless, be held from shifting or displacement in the holder and the wrenches which have been removed, can be replaced in their respective pockets in the holder without any necessity for moving the other wrenches to make room for the wrenches being replaced. In this modified construction, the hinged ends of the

legs or end bars 15 of the retaining member are connected by a longitudinal side or tie bar 25 which prevents the spreading of these end bars or legs. As shown, this tie bar is formed by integral inwardly extending continuations of the legs, which extensions are welded or otherwise suitably joined together at their meeting inner ends.

I claim as my invention:

1. A wrench set unit comprising a set 75 of wrenches arranged side by side, and a holder extending about and holding said wrenches against lateral separation and having parts which interabut with parts of said wrenches to prevent substantial longitudinal movement of the wrenches in either direction in the holder, said holder comprising a skeleton wire body having bars extending across the edges of the several wrenches at one side of the set and being formed with bends providing individual open-sided holding seats for the several wrenches, and a skeleton wire retaining member which extends across the edges of the several wrenches at the opposite side of the set and is movable to open and close the holder, whereby one or more of the wrenches can be removed from the holder without disturbing the remaining wrenches when said retaining member is in open position.

2. A holder for a set of tools comprising a skeleton wire body having opposite end bars at one side of the holder, a side bar connecting corresponding ends of said end bars, and cross bars extending from the opposite ends of said end bars, and a wire retaining member having end bars arranged opposite to the end bars of the body and hinged to the ends of said cross bars, and a side bar 100 connecting the free ends of said end bars and extending substantially parallel with the side bar of the body, said retaining member being adapted to swing on its hinges toward and from the body, and means for releasably securing the retaining member in closed position.

3. A holder for a set of wrenches having opposite end enlargements and reduced shanks extending between and connecting 115 said enlargements, said holder comprising a body formed of a single piece of wire bent to form end bars which extend across the shanks of the several wrenches of the set between and adjacent the end enlargements of 120 the wrenches, a side bar connecting corresponding ends of said end bars, and cross bars extending transversely from the opposite ends of said end bars, and a retaining member formed from a single piece of wire 125 bent to form end bars hinged at one end thereof to said cross bars of the body and a side bar connecting the opposite ends of said end bars, said side bars of the body and retaining members having integral portions 130

adapted for releasable engagement to hold said retaining member in closed position.

4. A wire holder for a set of tools comprising a body member and a retaining member each consisting of a single piece of wire bent to form diverging legs, the diverging legs of the body and retaining member being disposed opposite to each other and hinged together at one side of the holder, and 10 the legs of the body and retaining member being connected by side bars extending lengthwise at the opposite side of the holder, said side bars of the body and retaining members being adapted for interlocking engagement with each other to releasably hold 15 said members from separation.
5. A holder for a set of wrenches adapted to extend about the wrenches to hold them against lateral separation, said holder com- 20

prising a body formed of a single piece of wire having connected and bars arranged to extend across the edges of the wrenches at one side of the set, and a retaining member formed of a single piece of wire having connected end bars arranged to extend across the opposite edges of the wrenches, the end bars of the body member and retaining member being hinged together at one side of the holder to adapt the retaining member and body member to move toward and from each other, and means for releasably securing the retaining member and body in connection with each other at the opposite side of the holder, the end bars of one of said members being bent to form separated seats for the wrenches. 70 75 80
